UNITED STATES PATENT OFFICE.

CHARLES F. ROPER, OF HOPEDALE, MASSACHUSETTS, ASSIGNOR TO DRAPER COMPANY, OF HOPEDALE, MASSACHUSETTS, A CORPORATION OF MAINE.

PICKER-STICK MOTION FOR LOOMS.

SPECIFICATION forming part of Letters Patent No. 781,680, dated February 7, 1905.

Application filed September 28, 1904. Serial No. 226,272.

To all whom it may concern:

Be it known that I, CHARLES F. ROPER, a citizen of the United States, and a resident of Hopedale, county of Worcester, State of Massachusetts, have invented an Improvement in Picker-Stick Motions for Looms, of which the following description, in connection with the accompanying drawings, is a specification, like characters on the drawings representing like parts.

This invention relates more particularly to that portion of the picker-stick motion of a loom often termed the "parallel motion," meaning thereby the mechanism which causes the picker to move in a path substantially parallel to the raceway of the lay.

My present invention has for its object the construction of a parallel motion comprehending certain novel features of construction and arrangement whereby the rocking shoe, to which the lower end of the picker-stick is secured, is prevented from lifting at each end of the stroke of the stick and given a bodily longitudinal movement as it rocks.

The various novel features of my invention will be fully described in the following specification and particularly pointed out in the appended claims.

Figure 1 is a front elevation of the right-hand side of a loom provided with a picker-stick motion embodying one form of my invention with the picker-stick at the outer end of its stroke. Fig. 2 is an inner side elevation of the parallel motion shown in Fig. 1 looking toward the right. Fig. 3 is a transverse sectional detail on the line 3-3, Fig. 1, looking toward the right. Fig. 4 is an outline or diagrammatic view of the shoe and the bearing-line of the support when the picker-stick is substantially at mid-stroke, and Fig. 5 is a similar view taken when the picker-stick is at the end of its inward stroke.

The picker-stick P, movable in the usual slot in the lay A³, the picker P^X, the movement of which is to be made substantially parallel to the raceway of the lay, and the lug-strap L, connecting the stick with the pick-motion, (partly shown at P', Fig. 1,) may be and are

all of substantially well-known and usual construction and operate in a manner familiar to those skilled in the art. A shoe is attached to the lower end of the picker-stick to rock on a stand or support mounted on the lay rocker-shaft A², Fig. 1, the shoe and its support embodying various novel features now to be described. The support comprises an elongated body portion 1, having a hub 2 to receive and be secured upon the end of the rocker-shaft, said support having a long straight trough-like seat, inclined side walls 3 thereof giving a V shape to the seat in cross-section, as shown in Figs. 2 and 3. In Figs. 4 and 5 and in Fig. 1 the bottom line or intersection of the side walls is indicated by the straight line 3^X. Upturned parallel ears 4 are formed on the support extending well above the trough-like bearing-surface, said ears having upwardly and outwardly inclined slots 5 formed therein for a purpose to be described, said slots having circularly-curved ends and short straight sides, as herein illustrated. The shoe is adapted to rock on the support between the ears 4 and herein the shoe 6, rigidly clamped to the lower end of the picker-stick by a bolt 7 and nuts 8 and provided with an adjusting-screw 9, Fig. 1, has its lower portion shaped to present a longitudinally-curved convex sole 10, the latter being V-shaped or wedge-like in cross-section, (see Figs. 2 and 3,) to coöperate with the seat-walls 3. Referring to Figs. 1, 4, and 5, it will be seen that as the shoe rocks upon the support the rising or falling movement of the picker will be compensated by the longitudinal curvature of the sole 10 of the shoe, so that the picker will move in a substantially straight line or path. The bevel-sided seat coöperates with the V shape of the sole to prevent any relative lateral movement of the shoe and support, so that there can be no twisting of the shoe or picker-stick during the movement thereof, the ears 4 assisting to prevent such lateral movement of the shoe. At the ends of the stroke there is a tendency of the shoe to lift from the support, such lifting being transmitted through the stick to the picker with objectionable re-

sults, as it will tend to displace the shuttle. Various means have been devised to prevent such lifting, and usually by means of a spring or springs connected with the lower end of 5 the picker-stick or with the shoe. In my present invention I have devised simple but positively-acting means to absolutely prevent such lifting and said means also facilitates the movement of the picker in a straight 10 path. To this end lateral projections or trunnions 11 are rigidly secured to the shoe at opposite sides thereof and enter and move in the slots 5 of the ears 4, hereinbefore described. A convenient form of construction 15 is shown in Fig. 3, the shoe being recessed at 13 and having a transverse hole 14 connecting the recesses, the cylindrical projections 11 having their inner ends reduced at 12 to seat in the recesses. A headed bolt 15 20 is extended through the projections and through the hole 14, a nut 16 being screwed onto the threaded end of the bolt to rigidly attach said projections to the shoe after they have been passed through the slots 5 and 25 seated in the recesses 13.

Referring to Fig. 1, the picker-stick is at the outer end of its stroke and the inner end of the sole 10 is elevated, the projections 11 being then at the upper ends of the slots 5, 30 and it will be manifest that no lifting of the shoe or picker-stick can occur when the parts are so positioned. As the picker-stick is swung inward the sole rocks on the bearing of the support 1, and the projections or trunnions 11 descend in the slots 5 until at mid-stroke the parts are in substantially the relative 35 position shown in Fig. 4, the coöperation of the projections with the sides of the slots 5 causing a slight bodily movement of the shoe outward 40 on the support as the rocking of the shoe pulls the stick downward far enough to counteract the tendency of the picker to rise as it moves inward. After the stick passes its central position the picker normally tends to descend 45 below a straight line; but this tendency is counteracted by the lift imparted to the shoe as it rocks from the position shown in Fig. 4 to that shown in Fig. 5. At the same time the projections rise in the slots 5 and simultaneously 50 act to impart a slight additional outward bodily movement to the shoe as they travel upward to the upper ends of the slots, finally assuming the position shown in Fig. 5 when the picker-stick is at the inner end of 55 its stroke. Manifestly no lift of the shoe can take place at such time, and on the outward stroke of the picker-stick the movements of the parts just described are reversed. The projections 11 appear to fulcrum upon and 60 move longitudinally over the inner sides of the slots on the inward stroke of the stick and to move and fulcrum on the outer sides of the slot on the outward stroke, the combined ac-

tion of such shifting fulcrum and rocking of the shoe-sole on the support 1 imparting a very 65 accurate movement to the picker.

A stirrup 17 is cast as an integral part of the shoe and depends therefrom beyond the outer sides of the ears 4, the stirrup loosely receiving or surrounding the outer end of the support without interfering with the rocking movement of the shoe. A spring 8^x, Fig. 1, is connected by a strap 18 with the stirrup to retract or assist in the outward movement of the picker-stick, the opposite end of the 75 spring being fixed, or it may be attached to the stirrup of the opposite picker-stick, both arrangements being employed in the art. In Figs. 4 and 5 I have omitted the stirrup.

Having fully described my invention, what 80 I claim as new, and desire to secure by Letters Patent, is—

1. In a device of the class described, a picker-stick, an attached shoe having a longitudinally-convex sole, a support for and upon 85 which the shoe rocks, and positively-acting means to prevent lifting of the shoe at each end of the stroke of the stick and to effect bodily longitudinal movement of the shoe as it rocks.

2. In a device of the class described, a picker-stick, an attached shoe having a longitudinally-convex sole, a support having an elongated, straight bearing for and upon 95 which the sole rocks, and means to positively shift the fulcrum of and also prevent improper lifting of the shoe from the support.

3. In a device of the class described, a picker-stick, an attached shoe having a longitudinally-convex sole, a support for and upon 100 which the shoe rocks, upturned ears on the support at opposite sides of the shoe and provided with diagonal slots and lateral projections on the shoe adapted to enter the slots and shift the fulcrum of the shoe as it rocks, 105 the connection formed by the projections and slotted ears positively preventing improper lifting of the shoe as it rocks.

4. In a device of the class described, a picker-stick, a shoe secured to the lower end 110 thereof and having a longitudinally-convex sole, a support for and upon which the shoe rocks, upturned, slotted ears on the support at each side of the shoe, lateral projections on the latter to enter the slots and bodily shift 115 the shoe upon the support as it rocks thereon, and means to prevent lateral twisting of the shoe upon the support.

In testimony whereof I have signed my name to this specification in the presence of two sub- 120 scribing witnesses.

CHARLES F. ROPER.
